E. FRISCH

WAXED WRAPPING PAPER AND METHOD OF MAKING THE SAME

Filed Feb. 11, 1924

Inventor:
Emile Frisch,
By Fisher, Towle, Clapp & Doan,
Atty.

UNITED STATES PATENT OFFICE.

EMILE FRISCH, OF CHICAGO, ILLINOIS.

WAXED WRAPPING PAPER AND METHOD OF MAKING THE SAME.

Application filed February 11, 1924. Serial No. 692,192.

To all whom it may concern:

Be it known that I, EMILE FRISCH, a citizen of the United States, residing in the city of Chicago, county of Cook, and State of Illinois, have invented certain new and useful Improvements in Waxed Wrapping Paper and Methods of Making the Same, of which I do declare the following to be a full, clear, and exact description, reference being had to the accompanying drawing, forming a part of this specification.

The present invention has for its object more particularly to provide an improved bread wrapper formed of waxed paper. In recent years, it has become customary to wrap loaves of bread in sheets of waxed wrapping paper that serve to keep the loaves in fresh condition and protect them against contamination by handling and by access of insects thereto. Ordinarily, the wrapping of loaves of bread is at the present time effected upon a wrapping and sealing machine, the waxed wrappers being folded and sealed about the loaves of bread as they pass through the machine. Whether wrapped by hand or by machinery, it is found in practice that the wax with which the wrapping paper is impregnated is apt to crack or crease where it is bent at various points and the creases or cracks thus formed in the wax appear upon the paper as fine white lines and are apt to give to the wrapped loaves the appearance of having been handled.

My present invention is designed to render less conspicuous the lines or creases that are apt to appear in the waxed wrappers, incident to the creasing or cracking of the wax, and to this end, my invention consists in printing the waxed sheets or wrappers with designs comprising a multiplicity of lines closely simulating in color the lines that are necessarily produced in the waxed wrappers incident to folding the same about the loaves of bread.

The accompanying drawing represents a plan view of a sheet of wrapping paper embodying my invention.

Referring to the drawing, A designates the body of a sheet of waxed wrapping paper, such sheet being ordinarily produced by subjecting a web of paper to a bath of paraffine wax, in manner well understood by those familiar with the art of making

waxed paper. Before the web or sheet has been waxed, there is printed thereon a suitable design that comprises a multiplicity of lines *a*, the printing of the sheet being effected with white ink or with ink that will most nearly simulate in color and appearance the color of the lines that appear in a sheet of waxed wrapping paper after it has been bent or creased to such extent as to crack or change the appearance of the surface of the waxed paper. The surface of the sheet of paper may be printed with any suitable design that will serve the purpose of my invention. Thus, for example, in the drawing, the design shown simulates in appearance spider webs having disposed thereon at different points panels *b* adapted to receive printed matter *c*, such as advertisements or the like, these panels being preferably printed in white ink and the advertisements or the like appearing thereon being printed in ink of a contrasting color. It is obvious, however, that the particular design printed upon the sheet may be varied without departing from the spirit of the invention. While a sheet of waxed wrapping paper made in accordance with my invention will, when folded or creased, show at points fine lines of whitish appearance, nevertheless, in view of the fact that the wrapping paper has a design in white printed upon its surface, will render the creases of the paper inconspicuous and hence when the loaves of bread or like articles are inclosed in such wrappers, the packages will present a fresher and more attractive appearance.

Having thus described my invention, what I claim as new and desire to secure by Letters Patent is:

1. As a new article of manufacture, a sheet of waxed wrapping paper having printed thereon in white ink a design comprising a multiplicity of lines, whereby lines resulting from the creasing of the paper are rendered inconspicuous.

2. The method of rendering inconspicuous the lines resulting from handling or creasing sheets of waxed wrapping paper, that consists in printing upon such sheets in white ink a design comprising a multiplicity of lines.

EMILE FRISCH.
